FAUCET SHELL

Stephen A. Young, Delphi, Ind.

Application May 27, 1954, Serial No. 30,683

Term of patent 14 years

(Cl. D91—3)

Fig. 1

Fig. 2

Fig. 3

Figure 1 is a top plan view of a faucet shell embodying my new design.

Figure 2 is a front elevation of the same.

Figure 3 is an end elevation of the same.

I claim:

The ornamental design for a faucet shell, substantially as shown.
